(57) **CLAIM**

The ornamental design for a lift wheel arm for an implement, as shown and described.

DESCRIPTION

FIG. 1 is a rear perspective view of a lift wheel arm for an implement showing our new design, the broken line showing of the journal areas of the arm being for illustrative purposes only and forming no part of the claimed design. FIG. 2 is a top view of the lift wheel arm for an implement design of FIG. 1.

FIG. 3 is a front view of the lift wheel arm for an implement design of FIG. 1.

FIG. 4 is a right side view of the lift wheel arm for an implement design of FIG. 1.

FIG. 5 is a left side view of the lift wheel arm for an implement design of FIG. 1.

FIG. 6 is a back view of the lift wheel arm for an implement design of FIG. 1; and,

FIG. 7 is a bottom view of the lift wheel arm for an implement design of FIG. 1.
